Patented July 31, 1928.

UNITED STATES PATENT OFFICE.

NATHAN W. PERKINS, OF EAST ORANGE, AND EMIL JOHN ENS, OF NEWARK, NEW JERSEY, ASSIGNORS TO ELLIS ADDING TYPEWRITER COMPANY, OF NEWARK, NEW JERSEY, A CORPORATION OF NEW JERSEY.

ADDING AND SUBTRACTING ACCUMULATOR.

Application filed October 19, 1926. Serial No. 142,580.

Our invention relates to a combined adding and subtracting accumulator for calculating machines and is an improvement on the adding and subtracting accumulator set forth in the patent to Halcolm Ellis No. 1,203,863, dated November 7, 1916.

In the "Ellis" patent aforesaid a single set of accumulator wheels which are adapted to be actuated by racks whose extent of movement is determined by the setting of the keys on the keyboard is used both for addition and subtraction. In the construction covered by that patent, carrying is effected by using a pivoted, reciprocating carrying 10

it may be in the form of a slot having no entrant part although such slot is of sufficient width to permit shifting of the pin so that the same result will be obtained.

5 Practical embodiments of the invention are set forth hereinafter and shown in the accompanying drawings in which:

Figure 1, is a section through the accumulator;

10 Fig. 2, is a plan view;

Fig. 3, is a detail side view of the single cam plate which we have invented;

Fig. 4, is an edge view of said cam plate.

15 Fig. 5 is a view like Fig. 1, showing a modification, certain parts being omitted for the sake of clearness; and

Fig. 6, is a view like Fig. 3, showing a modified form of Y slot.

20 Fig. 7 is an edge view of the modification shown in Fig. 6.

Reference is to be had to the Ellis Patent No. 1,203,863 for a disclosure of elements and mechanisms related to our combined adding and subtracting accumulator, as we have 25 only illustrated those parts of the accumulator found in the said Patent 1,203,863 which are directly related to our present improvements.

The frame which carries the accumulator 30 section comprises plates N53 connected by rods N4.

35 The swinging accumulator frame appears at 50N, being pivoted and operated in a manner which will be clear from the said Ellis patent.

The shaft which carries the accumulator wheels N50 is shown at N2. Each accumulator wheel, except the highest of the series, carries a two-pointed cam N51.

40 It will be understood that Fig. 2 is broken away and only shows certain ones of the accumulator wheels.

The accumulator frame 50N swings on the shaft N5.

45 The adding hook appears in each instance at N60 and the subtracting hook in each instance is shown at N61. For a disclosure of detail views of these hooks, reference is to be had to Figs. 34 and 36 of No. 1,203,863.

50 The springs which actuate the hooks N60 and N61 are shown at N86.

55 The reciprocating detent or carrying device which is movable in one direction for effecting carrying during an adding operation appears at N54, being pivoted to the frame N53 at N16.

In Fig. 1 the accumulator frame and the accumulator wheels are shown in normal position, cam N51 being at the zero position, 60 one of the points thereof abutting the adding hook N60, the detent N54 being in engagement with the accumulator wheel, in each instance. The hooks N60 and N61 are pivoted on shaft N3.

65 The shift bar is shown at N90. The hook

N60 has the projections *a* and *w*, and the hook N61 has the projections *b* and *y*.

Reference is to be had to the aforesaid Ellis Patent 1,203,863 for a disclosure of the parts previously, specifically described.

70 In the accumulator mechanism of the Ellis Patent 1,203,863 two controlling mechanisms, namely, two cam plates appearing in Figs. 35 and 37 of said Ellis patent are used to control the swinging of the reciprocating 75 carrying device or detent N54.

Our improvements eliminate the adding and subtracting cam plates shown in Figs. 35 and 37 of Patent 1,203,863 and in lieu thereof we provide a single controlling 80 mechanism, namely, a cam plate such as appears in detail at N257, Figs. 3 and 4 or as having the modified cam slot shown in Fig. 6. This cam plate serves the functions of the two cam plates in question. It is pivoted at N15 and is provided with a Y-shaped cam slot appearing at YS (Figs. 1, 3, 4) or a cam slot of modified form such as appears at YSS, Fig. 6. The said slot receives pin N13 which projects from the detent. This 90 pin is adapted to pass into either of the branches B, B' of the cam slot YS or from one side to the other side of the wide part of the slot YSS, if a slot such as shown in Fig. 6 be used. Each cam plate N257 is actuated 95 by a spring N87.

Referring first to Figs. 1, 2, 3, to determine the branch, B, or B', which will be selected, there is provided a selective bail 73N which is pivoted at one end at 116N and 100 at the other end at N20N. A part of the frame appears at N45.

The bail 73N is connected to the respective studs or pins N13 of the various detents N54 by springs S.

105 Referring now to Fig. 6, if the tension of the springs S is made heavy enough, the slot in cam plate N257 may be of the shape shown at YSS because the tension of the springs will be sufficient to hold the pins 110 N13 against the outline or margin of said slot YSS, which is of the same general outline as the slot YS, except that the part which projects into the slot is omitted. We also wish it understood that the stud N13 115 could be provided on the combined adding and subtracting cam plate N257 and that the cam slot YS YSS might be provided on the detent N54.

120 The bail carries a stud N21N which is connected by a link 75N to a crank 76N at N22N, said crank being fastened to the shaft of the shift bar N90.

It is not necessary to employ a bail 73N which is pivoted, as any mounting enabling 125 the bail to shift will serve the purpose.

For instance, in Fig. 5 the end plates and one or more of the intermediate plates N53 are provided with guiding upper edges, and the bail 73N is slidably mounted on said 130

guiding edges, said bail being provided with arms or links N75N which are directly pivoted at N22N to two cranks 76N fastened to the ends of the shift bar N90, one of said cranks appearing in Fig. 5, the other one not being shown. Springs S which connect the bail 73N to the respective pins N13, as in the construction shown in Figs. 1 and 2, hold the bail against the tops of the plates N53.

10 The projections *a* and *b* on the adding hooks N60, N61 co-operate with the shift bar N90 in the manner set forth in the Ellis Patent No. 1,203,863.

15 The projections *w*, *y* on the hooks N60, N61 co-operate with parts *x* and *z* of the cam plate N257.

According to the setting of the shift bar N90, one of the hooks N60, N61 will be locked out while the other of said hooks 20 will be free for action. The turning of the shaft of the shift bar N90 positions the bail 73N at one side or the other of the dead center and consequently the tension of the springs S will shift the detents N54 in one 25 direction or the other to effect carrying during an adding operation or during a subtracting operation.

Thus, the single cam plate N257 performs all of the functions of both the adding cam 30 plate and the subtracting cam plate of the Ellis Patent 1,203,863.

Operation.—As shown in Figs. 1 and 5, the parts are in position for the performance of addition, the accumulator being "clear".

35 When the mechanism is tripped, the single cam plate N257 swings on its pivot N15, causing detent N54 to move a distance of one tooth, thereby advancing the accumulator wheel N50 of the next higher order in 40 the series of wheels, a distance of one tooth, thus effecting transfer or carrying.

This action will occur either when the mechanism is set for addition, or when it is set for subtraction.

45 When the shift bar N90 is turned in one direction, it frees one of the hooks N60, N61, enabling the spring of that hook to snap it into position for co-operation with the trip cam N51, said shift bar at the same time locking the other hook in inoperative position. When the shift bar is turned in the opposite direction, it frees the other one of the hooks N60, N61 for co-operation with the cam N51 and locks the remaining hook 55 in inoperative position.

As shown in Figs. 1 and 5, the shift bar N90 is set to condition the accumulator for addition, said bar then engaging the shoulder or lug *b* of the subtracting hook N61 and holding said hook back against the tension of its spring so that its point or tooth cannot be engaged by the trip cam N51 on wheel N50. The adding hook N60 being now freed from restraint by the shift bar 60 N90, its spring N86 positions said adding

hook N60 so that its point is in the path of the tooth of trip cam N51. At the proper time, the trip cam N51 can wipe against the point on the end of the adding hook N60, press it back and disengage its lug *w* from 70 the part *x* on plate N257, thus releasing the cam plate N257 which thereupon is shifted by its spring N87, causing detent N54 to turn the wheel N50 of the next higher order 75 a distance of one tooth, thus effecting carrying or transfer.

When the shift bar N90 is turned in the opposite direction, it disengages from the lug *b* of subtracting hook N61, whereupon 80 the spring N86 for said hook snaps it into position where its point will lie in the path of the tripping cam N51, and said bar N90 then engages the lug *a* on adding hook N60, pushing it back to inoperative position. Carrying may then take place during a subtracting operation, when the subtracting hook N61 is tripped by cam N51, because 85 the tripping of the hook N61 will disengage its lug *y* from the part *z* of the cam plate N257 which will then be snapped by its 90 spring N87, causing the detent N54 to be shifted a distance of one tooth in a direction the reverse of that taken by said detent N54 when carrying during an adding operation.

As previously explained, the turning of 95 the shift bar N90 so positions the bail 73N that the springs S will shift all of the detents N54 in the proper direction to effect carrying during an adding or a subtracting operation. 100

The accumulations are stored in the wheels N50 by the usual racks of the Ellis machine, and the parts co-operate with, and are restored by, a restraining bar, as disclosed, respectively, at R50 and N49, Ellis Patent 105 1,203,863.

Similarly, the frame 50N which carries the accumulator wheels N50 is lowered and raised in the same general manner as set forth in said Patent 1,203,863. 110

What we claim is:

1. In an adding and subtracting mechanism, the combination with accumulator wheels, of a reciprocatory carrying device 115 for each accumulator wheel, and a single, rockable adding and subtracting controlling mechanism for each wheel adapted to co-operate with the carrying device thereof to shift it in one direction or the other, whereby carrying may be effected either in an adding or a subtracting operation.

2. In an adding and subtracting mechanism, the combination with accumulator wheels, of a reciprocatory carrying device 120 for each accumulator wheel, a single, rockable adding and subtracting controlling mechanism for each wheel adapted to co-operate with the carrying device thereof to shift it in one direction or the other, whereby carrying may be effected either in an 130

- adding or a subtracting operation, and selective means for determining the action of said combined adding and subtracting controlling mechanism.
3. In an adding and subtracting mechanism, the combination with accumulator wheels, of a reciprocatory carrying device for each accumulator wheel, and a combined adding and subtracting controlling mechanism, for each wheel adapted to co-operate with the carrying device thereof to shift it in one direction or the other, whereby carrying may be effected either in an adding or a subtracting operation, and selective means for determining the action of said combined adding and subtracting controlling mechanism comprising a movably mounted member, springs connecting said member to the respective reciprocatory carrying devices, and means for shifting said movably mounted member to change the position of the springs for the purpose of changing the direction of travel of the reciprocatory carrying devices when said reciprocatory devices are freed for action.
4. In an adding and subtracting mechanism, the combination with accumulator wheels, of a reciprocatory carrying device for each accumulator wheel, a combined adding and subtracting controlling mechanism for each wheel adapted to co-operate with the carrying device thereof to shift it to one direction or the other, whereby carrying may be effected either in an adding or a subtracting operation, and selective means for determining the action of said combined adding and subtracting controlling mechanism comprising a shiftable bail, springs connecting the bail to the respective reciprocatory carrying devices, said springs being adapted to move when the bail is shifted to thereby determine the direction of pull on the reciprocatory carrying devices and hence the direction of movement of said reciprocatory carrying devices when said devices are freed, and means for determining the action of said bail and said combined adding and subtracting controlling mechanism.
5. In an adding and subtracting mechanism, the combination with accumulator wheels, of a reciprocatory carrying device for each accumulator wheel, a single movable combined adding and subtracting controlling member having a camming connection to the reciprocatory carrying device which enables said carrying device to be shifted in one direction for addition and in the opposite direction for subtraction, and selective means for determining the direction in which the reciprocatory carrying device will move.
6. In an adding and subtracting mechanism, the combination with accumulator wheels, of a reciprocatory carrying device for each accumulator wheel, a single movable combined adding and subtracting controlling member having a camming connection to the reciprocatory carrying device which enables said carrying device to be shifted in one direction for addition and in the opposite direction for subtraction, and selective means for determining the direction in which the reciprocatory carrying device will move.
7. In an adding and subtracting mechanism, the combination with accumulator wheels, and a reciprocatory carrying device for each wheel, of a pivoted cam plate having a cam co-operating with said reciprocatory carrying device in each instance, the cam of said cam plate being adapted to effect shifting of said reciprocatory carrying device in one direction or the other to cause carrying either in addition or subtraction, and means for selectively determining the action of each of said cam plates.
8. In an adding and subtracting mechanism, the combination with accumulator wheels, and a reciprocatory carrying device for each wheel, of a pivoted cam plate having a cam co-operating with said reciprocatory carrying device in each instance, the cam of said cam plate being adapted to effect shifting of said reciprocatory carrying device in one direction or the other to cause carrying either in addition or subtraction, a swinging bail, independent coil springs connecting said bail to the respective reciprocatory carrying devices, and selective means co-operating with the respective cam plates and with the bail to determine the position of the bail and of the springs and the action of the cam plates.
9. In an adding and subtracting mechanism, the combination with accumulator wheels, of a reciprocatory carrying device for each wheel, a plurality of swinging plates, each having a Y-shaped cam slot receiving a part of the reciprocatory carrying device, a bodily shiftable member, independent coil springs connecting said member to the respective reciprocatory carrying devices, and means for selectively determining the shifting of said member and the action of said cam plates whereby the direction of pull of the springs on the reciprocatory carrying device will determine the direction in which said devices will move when freed.
10. In an adding and subtracting mechanism, the combination with accumulator wheels, and a reciprocatory carrying device for each wheel, of a combined adding and subtracting controlling member for each re-

ciprocator carrying device, said members having camming connection with the respective carrying devices, spring means co-operating with the reciprocator carrying devices, said spring means being operable to move the carrying devices in one direction or the other, and selective means for determining the action of said spring means and said combined adding and subtracting controlling means.

In testimony whereof we affix our signatures.

10
